CLAIM

The ornamental design for a trunk organizer, as shown and described.

DESCRIPTION

FIG. 1 is a perspective view of a trunk organizer showing our new design, shown mounted on the inside of a trunk lid of an automobile to show the environment of its use, it being understood that the broken line showing of the trunk lid and automobile are for illustrative purposes only forming no part of the claimed design;

FIG. 2 is an enlarged front view thereof;

FIG. 3 is an enlarged right side view thereof, the left side being a mirror image thereof;

FIG. 4 is an enlarged rear view thereof;

FIG. 5 is an enlarged top view thereof; and,

FIG. 6 is an enlarged bottom view thereof.

1 Claim, 3 Drawing Sheets
